UNITED STATES PATENT OFFICE.

WILLIAM SODEMANN, OF ST. LOUIS, MISSOURI.

ROOF-VENTILATOR.

1,235,609.

Specification of Letters Patent.

Patented Aug. 7, 1917.

Application filed April 14, 1916. Serial No. 91,073.

To all whom it may concern:

Be it known that I, WILLIAM SODEMANN, a citizen of the United States, residing at the city of St. Louis and State of Missouri, 5 have invented a new and useful Roof-Ventilator, of which the following is a specification.

This invention relates to ventilators of the type employed above the roofs of buildings and the like.

The object of the invention is to provide an efficient and simple ventilator including an outlet pipe having communication with the interior of the building or structure to 15 be ventilated, and a separate surrounding case forming a passage for directing currents of air past the upper open end of the outlet pipe whereby the siphon or suction principle or action of the air currents is 20 employed to accelerate the discharge or withdrawal of the air from the building, in combination with a relatively large chamber into which said pipe and case open, said chamber opening to atmosphere at its upper 25 and lower ends and inclosing spaced protecting covers placed in a novel arrangement to protect the discharge end of the outlet pipe.

Other objects reside in the particular construction and arrangement of the parts and 30 will be apparent from the following description without specific mention, reference being made to the drawing in which—

Figure 1 is a plan view of my improved 35 ventilator.

Fig. 2 is a side elevation.

Fig. 3 is a vertical sectional view on the line 3—3 of Fig. 1.

In the specific embodiment illustrated the 40 pipe 1 is composed of sheet metal and is in the form of a tube adapted to be connected to the passage communicating with the interior of the structure to which the ventilator is to be applied. It is intended that 45 the air from the passage leading into the building shall be received within the lower end of the pipe 1 and discharged from the upper end thereof, and that such movement of the air from within the building shall be 50 accelerated by currents of air directed adjacent to the upper open end of the pipe 1 to cause a suction action to aid in ventilating the building. For applying the currents of air in this manner the pipe 1 is inclosed

within a case or shell 2 forming an annular 55 passage 3 open at its upper and lower ends and completely surrounding the upper part of the pipe 1. The case or shell 2 may be supported in any preferred manner as by supporting arms 4 connecting the case 2 60 with the pipe 1, so that when said parts are assembled they are relatively stationary.

A deflecting shelf or apron 5 is attached to the pipe 1 and extends obliquely downwardly and outwardly below the lower open 65 end of the passage 3, so that the air or wind coming in contact with the apron 5 will be deflected upwardly thereby into the passage 3. In this manner better and freer circulation of the air currents through the 70 passage 3 is obtained so that continuous currents of air are passing through the passage 3 adjacent to the upper open end of the pipe 1, and continuously serve to draw air from the pipe 1 thereby maintaining more perfect 75 ventilation of the building.

As shown the upper end of the case 2 is slightly above the end of the pipe 1 so that all of the air passing through the passage 3 is directed properly relative to the open 80 end of the pipe 1.

An annular plate 6 of a diameter larger than the diameter of the case 2 and provided with a central opening 7 is supported in axial alignment with the pipe 1 and case 85 2 by a number of supporting arms 8 having their upper ends connected to the plate 6 and their lower ends preferably to the pipe 1. The opening 7 provides a passage for the air, and the surrounding portion of 90 the plate 6 deflects the rain and other falling substances so that they will drop outside the case 2 and will not be permitted to fall within the pipe 1. Above the plate 6 an additional protecting plate 9 is supported, 95 said plate being of larger area than the opening 7 so that the rain and other substances falling upon the plate 9 will be deflected thereby on to the oblique plate 6 and discharged therefrom, thus preventing any 100 of such substances from entering the ventilating pipe 1. The plate 9 is supported above the plate 6 by supporting members or brackets 10 holding said plate 9 properly in position to deflect the falling substances, 105 as described.

The large cylinder 11 is supported at the upper portion of the device and surrounds

the upper end of the case 2, so that the air currents from the passage 3 and the air coming from the pipe 1 are discharged into the chamber formed by the cylinder 11 below the plate 6 which is also within said cylinder 11. It will be observed that the upper and lower ends of the cylinder 11 are open and that an annular passage is formed between the lower end of the cylinder 11 and the upper end of the case 2, thus enabling currents of air to pass upwardly into the cylinder 11 to coöperate with the currents of air coming from the passage 3. The cylinder 11 is supported in connection with the case 2 by connecting devices 12 and is further braced in connection with the plate 6 by connecting members 13.

By reference to Figs. 2 and 3, it will be observed that the plate 9 is supported in a plane above the upper end of the cylinder 11, thus permitting air currents or the wind to move freely across the upper end of the cylinder 11 below the plate 9 and above the plate 6, so as to assist in withdrawing from the cylinder 11 all of the air entering into it.

By the foregoing construction it will be observed that I attain a continuous upward movement of the air through the passage 3 and also through the passage at the lower end of the cylinder 11, and that such movement is maintained to a maximum degree, because of the substantially unobstructed construction and arrangement of the passages and further because of the provision 35 of the apron 5.

It will also be observed that the top plate 9, being supported somewhat above the plane of the upper end of the cylinder 11, provides a space for cross currents of air which cause 40 rapid withdrawal or discharge of all of the air entering the cylinder 11. There is no restriction or obstruction to the free movement of the air, but on the contrary such movement is increased by the application of the 45 several currents of air applying the principles of suction to the ventilator pipe.

What I claim and desire to secure by Letters Patent, is:—

1. In a ventilator, a ventilating pipe, a 50 separate case surrounding the ventilating pipe and being open at its upper and lower ends, an apron extending obliquely downwardly and outwardly from the ventilating pipe below said case to deflect the air into 55 the lower end of said case, a cylinder encircling the upper ends of said pipe and case and being open at its upper and lower ends, and plates supported in position to prevent rain and other falling substances 60 from entering the ventilating pipe.

2. In a ventilator, a pipe for discharging air from the building, a separate case surrounding said pipe and extending a distance above the upper end thereof and forming a 65 passage around the discharge pipe open at

its upper and lower ends, a device supported by said discharge pipe for deflecting air into the lower end of said case, a cylinder inclosing the upper ends of the discharge pipe and the case, a deflecting plate in axial alinement 70 with said discharge pipe and provided with a central opening, and a plate supported above said opening.

3. In a ventilator, a ventilating pipe for discharging air from the building, a case 75 opening to atmosphere at its upper and lower ends surrounding said ventilating pipe, a device for deflecting air into the lower end of said case, a cylinder inclosing the upper ends of said two passages and 80 opening to atmosphere at its upper and lower ends, a plate supported above the ventilating pipe and having a central opening, and a plate supported above said opening and above the plane of the upper end of said cylinder, whereby cross currents of air may 85 move between said two plates transversely of said pipe and case to draw out the air discharged into said cylinder by said pipe and case.

4. In a ventilator, a ventilating pipe, a case surrounding said ventilating pipe and opening to atmosphere at its upper and lower ends and having its upper end above the end of said pipe, a deflecting apron extending 95 obliquely downwardly and outwardly below said case whereby currents of air are deflected upwardly into said case, a cylinder encircling the upper end of said case and having a passage thereinto around said case, whereby currents of air may rise into said cylinder, a plate within said cylinder arranged to deflect falling substances through the lower end of said cylinder outside of said case, said plate being provided with a central opening above the ventilating pipe, and a plate supported above said opening and above the plane of the upper end of said cylinder.

5. In a ventilator, the combination of a 110 ventilating pipe, a case encircling said pipe and forming a continuous annular passage around the ventilating pipe open at its upper and lower ends, a cylinder surrounding the upper end of said case and having open upper and lower ends, a deflecting plate above said pipe and case preventing falling substances from entering said pipe and case and having a central opening above the ventilating pipe, and an additional plate above 115 said deflecting plate of larger area than the opening therethrough.

6. In a ventilator, the combination of a 125 ventilating pipe, a relatively large cylinder surrounding the upper portion of said pipe and arranged to receive the air discharged therefrom, a case surrounding said pipe and forming a passage around said pipe for admitting air into said cylinder adjacent to the upper end of said pipe, a device for deflect- 130

ing air into said case, and spaced deflecting plates supported above said pipe and case and arranged to deflect falling substances outside of said pipe, one of said plates being within said cylinder and the other of said plates being above the plane of the upper edge of said cylinder.

In witness whereof, I have signed this specification in the presence of two subscribing witnesses.

WILLIAM SODEMANN.
